UNITED STATES PATENT OFFICE.

AUSTIN A. FRYE, OF LOWELL, MASSACHUSETTS.

FLY-PAPER HOLDER.

No. 918,309.

Specification of Letters Patent.

Patented April 13, 1909.

Application filed June 29, 1908. Serial No. 440,820.

To all whom it may concern:

Be it known that I, AUSTIN A. FRYE, a citizen of the United States, residing at Lowell, in the county of Middlesex and 5 Commonwealth of Massachusetts, have invented a certain new and useful Improvement in Fly-Paper Holders, of which the following is a specification.

This invention relates to an improvement 10 in fly-paper holders, the general objects of the same being to furnish a light inexpensive device, constructed of wire, adapted to hold securely a sheet of sticky fly-paper flat and to support it in an elevated position 15 out of danger of contact with clothing and other articles that might be injured thereby, and to facilitate the introduction of the paper to said holder and its removal therefrom.

20 In the accompanying drawing, Figure 1 is a plan of a fly-paper holder provided with my improvement; Fig. 2, an end elevation of the same; Fig. 3, an enlarged plan of a part of the same, showing a means of holding 25 the table or paper-supporting wires in place; Fig. 4, a vertical section of one side of the frame and a side elevation of parts of some of the paper-supporting wires.

A represents a skeleton wire frame, 30 rectangular in plan, having straight sides a a^1 and having ends a^2 a^3 which are each provided in the middle with an eye a^4 a^5 , said ends sloping downward from said eyes to said sides.

35 The table or paper-supporting surface of the device comprises the sides a a^1 and cross-wires B B^1 which terminate in hooks b b^1 which reach under, outside of and in over 40 said sides, said cross wires being represented as V-shaped wires twisted together in the middle at b^3 in parts, two such pairs being shown in Fig. 1.

Between the pairs of cross-wires is arranged a brace and tie wire C which holds 45 the sides a a^1 at the proper distance from each other, said wire C reaching below said sides and being bent up around said sides into eyes c c^1 (Figs. 1, 3 and 4) at each end.

The accidental displacement of the wire 50 C and the adjacent hooks b b^1 on the side wires a a^1 is guarded against by loops D

(Figs. 3 and 4) of fine wire passed around all said wires.

The bail or suspending wire E is provided with a central hook, loop e or equivalent 55 means of engaging a string or cord (not shown) by which it may be hung from a gas-fixture, chandelier or other overhead device in an obvious manner, and from said loop e , the arms e^1 e^2 of the bail are bent 60 downward and terminate in hooks e^3 e^4 adapted to engage the eyes a^4 a^5 (Fig. 1) of the ends a^2 a^3 . These hooks e^3 e^4 may be disengaged from the eyes a^4 a^5 for transportation and the bails placed upon the top 65 holder, the holders being nested together.

The paper is introduced by shoving one of the narrow ends of the paper below one of the ends of the holder and above the cross-wires, but below the hook e^3 e^4 . The 70 paper should be wide enough to fill the space between the bottom of the hooks snugly and it will be better if the paper has to be slightly bent upward in the middle to get it in place between the bottoms of the 75 hooks.

It will be seen that the bail is of such proportions and arrangement that when the bail falls, it is held out of contact with the base or table of the holder by the hooks b b^1 80 and by the height of its pivots and that thus the bail is prevented from being soiled by the sticky coating of the fly-paper.

The paper in the holder when the latter 85 is tipped over is prevented from coming in contact with the counter, table or floor on which it falls by the ends a^4 a^5 being engaged above the paper supporting surface. The sticky fly-catching paper is almost 90 entirely uncovered, the bail affording no obstruction to the passage of the flies to the paper and offering little resting place for the flies.

I claim as my invention:—

1. A fly-paper holder formed of wire having 95 a frame rectangular in plan and provided with straight sides and with ends each having an eye in the middle and being inclined downward in opposite directions from said eye to said sides, cross-wires connecting said sides and forming a support for said fly-paper and having hooks which extend 100

inward above said sides, and a bail having hooks to engage the eyes in said ends.

2. A fly-paper holder having a skeleton wire frame with parallel sides, ends having each an eye in the middle and inclined upwardly from said sides to said eye, cross-wires connecting said sides and having hooks which reach inward above said sides, and a

bail having hooks to engage the eyes in said ends.

In witness whereof, I have affixed my signature in presence of two witnesses.

AUSTIN A. FRYE.
